UNITED STATES PATENT OFFICE.

WILLIAM E. WHITTEMORE, OF HARTFORD, CONNECTICUT.

DESIGN FOR A CUSPIDOR-CLEANER.

SPECIFICATION forming part of Design No. 28,707, dated May 24, 1898.

Application filed April 9, 1898. Serial No. 677,097. Term of patent 14 years.

To all whom it may concern:

Be it known that I, WILLIAM E. WHITTEMORE, a citizen of the United States, residing at Hartford, Connecticut, have invented 5 and produced a new and original Design for Cuspidor-Cleaners, of which the following is a specification, reference being had to the accompanying drawing, forming part thereof.

The figure of the drawing is a perspective 10 view of a cuspidor-cleaner having my design.

As shown in the drawing, the leading or material feature of my design consists in a curved circular bristles portion, with the handle-rod and handle extending at right angles 15 to the bristles portion.

The bristles portion 1 is circular in cross-section and is semicircular in longitudinal section. The handle-rod 2, with the handle 3, extends from one end of the curved bristles portion at right angles to the plane of curvature of the bristles portion. 20

Having now described my invention, what I claim as new, and desire to secure by Letters Patent, is—

The design for a cuspidor-cleaner as herein 25 shown and described.

WILLIAM E. WHITTEMORE.
